UNITED STATES PATENT OFFICE.

JULIUS LARSEN, OF COPENHAGEN, DENMARK, ASSIGNOR, BY MESNE ASSIGNMENTS, TO
LARSEN MACHINES COMPANY, A CORPORATION OF NEW YORK.

WELTING-MACHINE.

No. 927,153.

Specification of Letters Patent.

Patented July 6, 1909.

Application filed September 22, 1908. Serial No. 454,227.

To all whom it may concern:

Be it known that I, JULIUS LARSEN, a citizen of the Kingdom of Denmark, and a resident of Vestergade 11, Copenhagen, Denmark, engineer, have invented new and useful Improvements in Welting-Machines, of which the following is a specification.

My invention relates to means for handling welts in welting machines and in other forms 10 of machines for sewing leather, my more particular purpose being to provide means whereby the welt is fed step by step into a position favorable for enabling it to be pierced by the needle.

Reference is to be had to the accompanying drawings forming a part of this specification, in which similar characters of reference indicate corresponding parts in all the figures.

Figure 1 is a front elevation of my device, showing it as applied to a machine for sewing leather welts; Fig. 2 is a side elevation of the device, showing it as viewed from a point at the left of Fig. 1; Fig. 3 is a detail showing how the welt is held in a position favorable for enabling it to be pierced by the sewing machine needle; Fig. 4 is a plan view of the welt handling device; Fig. 5 is an inverted plan of the stitch plate 30 which, to some extent, serves as a guide for the moving welt.

At 1 is shown the head or column of the sewing machine, and below it is an oscillatory ring 2 which contains a shuttle box. 35 2^a. Mounted upon the upper edge of the oscillatory ring 2 and partially encircling the upper portion of the shuttle box 2^a is a carrier ring 3 which travels with these parts. Mounted upon the oscillatory ring 2 and extending upwardly therefrom is a pawl 4 which is engaged by a leaf spring 4^a. The upper end of this pawl is disposed adjacent to a circular row of teeth 5 with which the carrier ring 3 is provided. The carrier ring 40 3 is provided with another circular row of teeth 7^a, this row being made up of smaller teeth and being also of slightly lesser diameter than the row of teeth 5.

At 7 is a welt which is to be fed, step by 50 step into a position favorable for enabling it to be sewed. At 8 is a leaf spring which presses gently upon the welt. At 9 is shown a stitch plate forming a part of a sewing machine. The leaf spring 8 is supported

upon the under side of this stitch plate by 55 aid of a bolt 10. A lever 11 is journaled upon a pivot pin 12 carried by lugs 13 which are integral with the oscillatory ring 2. The lever 11 is provided with a slot 11^a through which the welt 7 is fed. The lever 11 at a 60 point below the pivot 12 is bent substantially to a right angle, its end being thus brought centrally beneath the oscillatory ring 2. This lower end of the lever 11 is provided with a convex bearing surface 11^b which rests 65 upon a mating bearing surface 14 carried by a cam lever 15. The purpose of this arrangement is to keep the bearing surface 11^b always central in relation to the oscillatory ring 2, notwithstanding the movement of 70 this ring. The cam lever 15 carries a cam roller 16 which is engaged by a rotary cam 17 driven by a shaft 18. As the cam 17 is turned, a rocking motion is conferred upon the cam lever 15, and consequently the lower 75 end of the lever 11 is caused to reciprocate in a vertical direction. This causes the upper end of the lever 11 to approach and recede from the carrier ring 3 and, consequently, the circular row of teeth 6. 80

A casing 19 is provided with a neck 20, and these two parts together are provided with a slot 21 for accommodating the lever 15, as will be understood from Fig. 1. Mounted upon the neck 20 is a stationary 85 plate 22 and extending over the latter is a projecting portion 23 of the oscillatory ring 2. Mounted upon the projecting portion 23 is a boss 24, and disposed adjacent to the latter is an arm 25 which, in any desired manner, is given a reciprocating motion. The movements of the arm 25, by actuating the projection 23 in one direction, causes the oscillatory ring 2 to turn in said direction. For the purpose of retracting the oscillatory 90 ring 2 I provide a spiral ring 26 which is connected with a post 27, the latter being secured directly upon the plate 22 and, consequently, being stationary. Another post 28 is mounted upon the plate 22 and journaled upon this post is a pawl 29, this pawl being in the same plane as the circular row of teeth 5. A spring 30 is connected with the pawl 29 and is also connected with a post 31, the latter being mounted upon the plate 100 22. The spring 30 tends to cause this pawl to engage the teeth 5.

For the purpose of supporting the oscil-

latory ring 2 I provide a spider 32. This spider is provided with a slot 32^a and fitting into the same is a supporting tongue 33 which is rigid with the frame work of the 5 sewing machine. Extending through the supporting tongue 33 is a pivot pin 34 which is connected rigidly with the spider 32, and is provided with a head 34^a in direct engagement with the supporting tongue 33. 10 The compressing spring 32^b engages the spider 32, being seated therein as indicated in the lower left-hand corner of Fig. 1. This spring also engages the lever 11 and tends to move this lever in normal position. The 15 oscillatory ring 2 rests upon the spider 32 which in turn practically hangs from the pivot pin 34, the latter being suspended from the supporting tongue 33, the spider 32 being provided with a slot 32^a for accommo- 20 dating this supporting tongue. The purpose in thus securing the oscillatory ring 2 is to give it due freedom of movement without the necessity for the supporting mechanism being in the way of the operator, or of 25 moving parts of the machine.

The stitch plate 9 is provided with an opening 35 to enable it to be fitted and held in position, and is further provided with channels 36 for guiding the upper edge of 30 the welt. The stitch plate 9 is further provided with a lip 37 integral with it, and is also provided with a channel 38 adjacent to this lip. At 39 is an opening and at 40 is a slot merging into this opening. The channel 38 serves as a guide for the welt. 35

At 41 is a sewing machine needle which is curved. At 42 is a strip of leather to be sewed upon a piece of stock 42^a, this piece of stock being for this purpose provided 40 with a portion 42^b so that this portion, the strip of leather 42 and the welt may be readily sewed together, as indicated in Fig. 3.

The operation of my device is as follows: The rotary motion being communicated to 45 the cam 17, this cam rocks the lever 15 in a vertical plane. This lever communicates motion to the lever 11, causing the same to rock upon the pivot 12. A reciprocating motion being given by the arm 25 and boss 50 24 to the oscillatory ring 2, this ring turns back and forth, being forced in one direction by the arm 25 and retracted by the spring 26. Each time the rocking lever 15 allows the lower end of the lever 11 to descend, the jaw 43 engages the welt 7 and grips it tightly 55 against the circular row of teeth 6. At the instant this occurs, the oscillatory ring 2 turns slightly in a clockwise direction according to Fig. 4, being actuated by a movement of the arm 25 against the boss 24, and this is followed immediately afterward by relaxation of the jaw 43 relatively to the welt. The result is that as the oscillatory ring 2 travels in one direction, it carries with 60 it the welt 17 which is momentarily secured

to it by the jaw 43, and as the oscillatory ring is retracted to its normal position by the spring 26 the carrier ring 3 is not moved backward, and consequently the welt is not disturbed by the return of the oscillatory ring to its normal position. The carrier ring is thus moved progressively around step by step, and the welt is fed step by step, in response to the movement of the oscillatory ring. The thrust of the needle 41 takes 75 place while the welt is stationary.

From the above description it will be seen, therefore, that I have produced a device for feeding the welt with a positive motion step by step, there being little or no chance for the welt to retrograde, and in doing this, after each movement the device holds the welt firmly in a suitable position to enable the curved needle to pierce the welt.

Having thus described my invention, I 85 claim as new and desire to secure by Letters Patent:

1. In a welting machine, the combination of an oscillatory ring, a carrier ring movable therewith in one direction, means for preventing retrogression of said carrier ring relatively to said oscillatory ring, mechanism for guiding a welt toward said carrier ring, a lever pivotally mounted upon said carrier ring, a jaw mounted upon said lever and adapted to engage and disengage said welt, and means for actuating said lever. 90

2. The combination of a carrier ring, means for turning the same step by step, a lever provided with an opening disposed adjacent to said carrier ring and adapted for feeding a welt through said opening to said carrier ring, means for turning said carrier ring and said lever upon an axis common to 100 said carrier ring, mechanism for retracting said lever, and a pawl for preventing retrogression of said carrier ring. 105

3. The combination of an oscillatory ring, means for actuating the same, a carrier ring mounted upon said oscillatory ring and turned thereby in one direction, means for retracting said oscillatory ring after each movement of the same, a lever mounted upon said oscillatory ring and provided with a jaw for forcing a welt against said carrier 110 ring while said oscillatory ring is being turned in one direction, and mechanism for actuating said lever for the purpose of causing said jaws to alternately engage and disengage said welt. 115

4. The combination of an oscillatory ring, a pivotal support therefor, a lever mounted upon said oscillatory ring and adapted to turn therewith as said oscillatory ring is rocked, said lever being provided with a portion extending into the axis of rotation of said oscillatory ring, a movable member extending across the axis of rotation of said oscillatory ring for the purpose of actuating 125 said lever, a jaw mounted upon said lever 130

and adapted to engage a welt, a carrier ring loose relatively to said oscillatory ring and disposed in the plane of said jaw for the purpose of receiving said welt, mechanism 5 carried by said oscillatory ring for turning said carrier ring, and means for preventing retrogression of said carrier ring.

Signed by me at Copenhagen, Denmark, this 3rd day of September, 1908.

JULIUS LARSEN.
